FUEL INJECTION VALVE FOR INTERNAL
COMBUSTION ENGINESEdward T. Vincent, Detroit, Mich., assignor to
Continental Motors Corporation, Detroit, Mich.,
a corporation of Virginia

Application April 23, 1931, Serial No. 532,261

9 Claims. (Cl. 123—32)

My invention relates to fuel injection engines and more particularly to engines of the compression ignition type and to the valve operating means for controlling the fuel injection.

5 Two well known systems of fuel injection for engines of this type are the constant pressure system and the jerk system. The former system gives the most power but more skill is required in maintaining the working parts in proper adjustment and the slightest wear of the timing and control mechanism, the cam in particular, may completely cut out one of the cylinders thereby reducing the engine power and overloading the other cylinders. Even though the wear is 10 not sufficient to cut out the cylinder, the power of the cylinder associated with the worn cam is materially reduced. The latter system is adapted for operation without frequent adjustments, but these adjustments are of a delicate and complicated nature requiring considerable skill and knowledge on the part of the mechanic. To be more specific it might be noted that the constant pressure fuel injection system is provided with means for mechanically opening and closing 15 the valve for controlling the injection of fuel into the cylinders, while the jerk system is provided with means for automatically opening and closing the valve in response to fuel pump operation, and usually provides an individual fuel pump for each 20 cylinder which measures and delivers a pre-determined amount of fuel. These pumps are relatively expensive besides providing a multiplicity of parts which are subjected to wear.

It is the object of my invention to construct 25 an engine of the fuel injection type having the advantages of both injection systems without the disadvantages by providing a fuel injection control mechanism having improved operating characteristics and which can be readily and quickly 30 assembled, or disassembled with an engine of the aforesaid type.

Another object of my invention is to construct 35 an engine of the compression ignition type provided with an improved mechanically released 40 valve means controlling the injection of fuel into the engine cylinders and with means responsive to a predetermined fall of fuel pressure in the source of fuel supply for automatically closing 45 said valve when a predetermined charge of fuel 50 has been injected into the cylinder.

For a more detailed understanding of my invention, reference may be had to the accompanying drawings which illustrate one form which my invention may assume and in which:

Figure 1 is a transverse vertical sectional view

of a compression ignition engine constructed in accordance with my invention and showing the fuel injection valve closed, said section being taken substantially on the line 1—1 of Figure 2,

Figure 2 is a plan view of the valve actuating 5 mechanism,

Figure 3 is a transverse vertical sectional view thereof showing the valve released and open,

Figure 4 is a detail view partly in section illustrating the manner in which the atomizer may 10 be assembled or disassembled, and

Figure 5 is a side elevational view of a multi-cylinder internal combustion engine of the compression ignition type and showing the fuel supply means. 15

An internal combustion engine of the fuel injection type and in particular one of the compression ignition type may be constructed of any suitable engine block structure 10 having one or more cylinders 11 in which the usual form of 20 pistons 12 are reciprocated, said pistons adapted to be connected in the usual way with the engine crankshaft 13. In the aforesaid type of engine, the fuel is sprayed into the cylinder where it ignites when coming into contact with the compressed air in the cylinder. The means for atomizing the fuel and the means controlling the injection of the fuel into the cylinder are preferably supported by the cylinder head 14 having suitable water jackets 15 communicating with the water 30 jackets 16 about the cylinder 11. Obviously the principles of my invention may be incorporated in fuel injection engines other than the compression ignition type, such as engines having a spark ignition and adapted for the injection of 35 lighter fuels, such as gasoline, and such lighter fuels may be injected directly into the cylinder or into an intake manifold associated therewith.

The cylinder head illustrated in the accompanying drawings is preferably provided with a 40 pillar 17 integrally formed with the cylinder head casting and arranged concentrically with respect to the cylinder axis, the pillar being bored out or otherwise constructed with a recess to receive the fuel nozzle and valve structure. The fuel 45 nozzle 18 may be of any standard construction, the same having a central opening 19, a valve seat 20, and one or more openings 21 in the tip of the nozzle. A valve guide, casing, or support 22 is secured in the head by means of bolts 23 or 50 other suitable means. In the illustrated embodiment of my invention, the valve structure is preferably constructed of a pair of upper and lower valve portions 24 and 25 respectively, the lower valve portion 25 provided with a valve element 55

26 at its lower end, a bead or flange 27 at its upper end, and longitudinal or spiral grooves 28. The upper valve portion 24 is guided directly in the valve guide or support and is arranged to abut the top face of the head 27 carried by the lower valve portion.

The valve structure is held on its seat by the pressure of the spring 60 acting through the lever mechanism A. The valve is released on actuating the mechanism thereby permitting the fuel pressure in the fuel supply line 37 or reservoir, commonly known as a "rail" to open the valve for injecting the fuel into the cylinder. Preferably this lever mechanism consists of a pair of cooperatively associated elements, such as the rocker arms 30 and 31, the former being pivotally supported on the rocker shaft 32 which is supported by the cylinder head 14 and actuated by cam 33 through the agency of the push rod 34 which engages one arm portion of the rocker arm through the agency of the adjustable ball and socket connection 30'. The cam 33 is driven in timed relation to the engine, by means of a camshaft 33a. The spring 60 is interposed between the other arm portion of the rocker arm 30 and the cylinder head 14, suitable spring abutments 61 being associated therewith, said spring abutments having balls 62 adapted for engagement within recesses 63 and 64 in the cylinder head 14 and rocker arm 30 respectively. The rocker arm 31 is pivotally supported as at 31' to a bracket 22' carried by the valve guide 22 and preferably integrally formed therewith. One arm portion of the rocker arm 31 is yieldingly forced upwardly by spring 60 thereby yieldingly urging the other arm portion into engagement with the upper end of valve portion 24 to yieldingly hold the valve closed. On actuating the push rod, the spring 60 is compressed thereby releasing the force holding the valve closed and permitting the fuel pressure to open the valve.

By employing the lever mechanism as described above a relatively light spring may be employed due to the fact that this construction permits the multiplication of forces and I have found that approximately a 200 lb. spring is generally sufficient for my purpose.

It will be noted that the atomizing device including the valve structure and associated mechanisms together with the rocker arm 31 may be readily assembled or disassembled from the cylinder head without disturbing the position of the rocker arm 30 or spring 60. Figure 4 illustrates how this unitary sub-assembly may be lifted out after the bolts 23 or other fastening devices which secure the sub-assembly to the cylinder head are removed. This assembly permits the engine to be readily and conveniently serviced, since one element of the control mechanism is removable with the valve, without disturbing the assembly of the other element or the spring and push rod associated therewith.

The fuel is conducted to a pump 35, through a pipe or conduit 36 from a fuel tank (not shown) or other source of fuel supply and thence forced into a fuel supply line or "rail" 37. Branch pipes or conduits 38 connect the "rail" with each of the cylinders, and if desired suitable valves 39 may be employed for respectively shutting off the supply of fuel to any one of said cylinders. A pressure regulating valve 40 may be employed to maintain a predetermined initial fuel pressure in the fuel line or "rail" at the beginning of the injection. I preferably connect the fuel pump up with the engine mechanism in such a way as

to actuate the pump to immediately bring the fuel pressure up to a predetermined maximum at the time of each injection. One or more strokes may be given to the pump, and one or more pump cylinders may be employed, but preferably the pump is constructed so that each stroke of the pump will bring the fuel pressure up to the required amount so as to provide a predetermined constant pressure in the "rail" at the time of injection.

The branch pipes or conduits 38 are arranged to be connected with a passage 41 in the valve guide by a union 42 or other suitable fitting. The passage 41 communicates with an enlarged bore 43 within the valve guide, the bore 43 being slightly larger than the head of the lower valve portion 25 to permit the fuel to flow freely past the head. A compression coil spring 44 bears on the head 27 yieldingly urging the valve on its seat. The fuel may flow through the groove 28 in the valve portion 25 into the nozzle chamber 45 formed by the reduced end portion of the valve portion 25.

Thus when the spring 60 is compressed, releasing the rocker arm, the fuel pressure may then lift the valve, this pressure exerting a lifting force on the valve portions 24 and 25 greater than the remaining forces tending to seat the valve structure. Immediately on lifting of the valve the fuel is sprayed into the cylinder under pressure, and the pressure of the fuel in the "rail" will rapidly fall, as well as the fuel pressure in the bore 43 that is in open communication with the "rail". When the fuel pressure falls a predetermined amount sufficient to allow the spring 44 to overcome the differential in pressure action on the valve portion 25, the spring 44 will force the lower valve portion 25 downwardly and separate the valve portions 24 and 25. The lower valve portion which carries the valve is quickly snapped down because as soon as the valve portions are separated, there is a bigger area exposed to the remaining fuel pressure tending to lower the valve. Thus I have obtained a quick automatic closing of the valve in response to a predetermined fall of fuel pressure. Even though the fuel pressure in the "rail" is built up before the upper valve portion is lowered again by the spring actuated rocker arm 31 the lower valve portion will remain seated, because of the differential in pressures acting down on the same. After the upper valve portion is forced down and seated on the head 27 of the lower valve portion by relieving the compression of spring 60, the differential of fuel pressure is reversed and the valve is held seated until the spring 60 is again compressed releasing the downward pressure of the spring 60 on the valve structure.

It will thus be noted that I have provided means for mechanically opening the valve and for automatically closing the valve, said means being of simple construction and readily maintained in service with a minimum of time and labor. The amount of fuel injected in the cylinder may be readily varied by varying the fuel pressure in the "rail" or supply line at the beginning of the fuel injection period by means of the control valve 40. It may be further noted that it is not necessary to provide a finely adjusted mechanism for controlling the valve lift as the same is lifted the maximum amount at each operation of the fuel injection means, whatever the engine speed or load may be. Thus I have provided what may be termed as a constant stroke means timed with the engine for controlling the opening of the fuel

injection valve and independent means regulating the quantity of fuel injected into the cylinder. A quick return of the rocker arm is not necessary as the valve is automatically closed independently of the valve releasing or opening mechanism.

Another advantage of my construction is that in the event of the failure of the spring 60 to function, or the failure of the upper valve portion to seat on the lower valve portion, the lower valve portion 25 will automatically cut off the cylinder associated therewith from the fuel supply line or "rail" as the valve remains closed due to the pressure of the spring 44 and the differential in fuel pressure acting in the direction of the valve seat.

The successful operation of an engine of the fuel injection type and in particular one of the compression ignition type depends largely on the proper timing and control of the fuel injection and my construction is simple but very effective in providing such a control without frequent adjustment. Wear such as will materially affect the operation of an ordinary engine having a constant pressure fuel injection system, will not affect the operation of my engine.

It will be further noted that my construction is well adapted for use with an engine of the heavy oil compression ignition type as well as with other fuel injection engines employing light fuel oils or other similar fuel.

Although I have illustrated but one form of my invention and have described in detail but a single application thereof, it will be apparent to those skilled in the art to which my invention pertains that various modifications and changes may be made therein without departing from the spirit of my invention or from the scope of the appended claims.

What I claim as my invention is:

1. A fuel injection apparatus for engines of the compression ignition type comprising, a fuel injection valve, a valve controlling shaft, a rocker arm pivoted to the engine and having a long arm and a short arm, a rod between said shaft and said long arm, a spring for loading said short arm, and a second rocker arm transmitting the load of said spring to said valve, said second rocker arm having a relatively long arm adapted for engagement with and actuation by the short spring loaded arm of said first rocker arm.

2. In a fuel injection apparatus for compression ignition engines, a fuel injection valve, a valve controlling shaft, first and second pivoted levers each having a long arm and a short arm, yielding means loading the short arm of the first lever and the long arm of the second lever, said second lever transmitting the load of the yielding means to actuate said valve, said first lever being adapted for actuation by said shaft independently of said valve actuating lever.

3. A fuel injection apparatus for engines of the compression ignition type including, a fuel injection valve unseated by fuel pressure, a valve controlling shaft, a compound lever mechanism adapted for actuation by said shaft and including a first lever having oppositely extending long and short arms, a spring for loading said short arm, the other of said arms being actuated by said shaft, and a second lever multiplying a lever having oppositely extending long and short arms, the long arm of said second lever overlapping the short spring loaded arm of said first lever and thereby loaded by the spring, the short arm of said second lever loading the valve to seat the same.

4. A fuel injection apparatus for engines of the compression ignition type including, a fuel injection valve unseated by fuel pressure, a valve controlling shaft, a compound lever mechanism adapted for actuation by said shaft and including a first lever having oppositely extending long and short arms, a spring for loading said short arm, the other of said arms being actuated by said shaft, and a second lever having oppositely extending long and short arms, the long arm of said second lever being loaded by the short spring loaded arm of said first lever, the short arm of said second lever loading the valve to seat the same, said lever arms of both levers being arranged to extend substantially in a common 15 plane at right angles to the valve axis.

5. A fuel injection apparatus for engines of the fuel injection type including, a fuel injection valve unseated by fuel pressure, a valve controlling device, a spring, and a lever mechanism consisting of first and second pivoted levers each having long and short arms, the short arm of said first lever engaging said spring and directly actuated by said device independently of said second lever to compress the spring, the short 25 arm of said second lever engaging said injection valve and having its long arm actuated by said spring to seat the valve.

6. A fuel injection apparatus for engines of the fuel injection type including, a fuel injection 30 valve unseated by fuel pressure, a valve controlling device, a spring, and a lever mechanism consisting of first and second pivoted levers, said first lever having a short arm for engaging said spring and an oppositely extending long arm directly 35 actuated by said device independently of said second lever to compress the spring, said second lever having a short arm engaging said injection valve and an oppositely extending long arm actuated by said spring to seat the valve.

7. A fuel injection apparatus for engines of the fuel injection type including, a fuel injection valve unseated by fuel pressure, a valve controlling device, a spring, and a lever mechanism consisting of first and second pivoted levers, said 45 first lever having a short arm for engaging said spring and an oppositely extending long arm directly actuated by said device independently of said second lever to compress the spring, said second lever having a short arm engaging said injection valve and an oppositely extending long arm actuated by said spring to seat the valve, said long arm of said second lever engaging the short arm of said first lever.

8. A fuel injection apparatus for engines of the fuel injection type including, a fuel injection 55 valve unseated by fuel pressure, a valve controlling device, a spring, a lever mechanism co-operating therewith and consisting of first and second pivoted levers each having long and short arms, the short arm of said first lever engaging the spring and having its long arm directly actuated by said device independently of said second lever to compress the spring, the short arm of said second lever engaging said injection valve 65 and having its long arm actuated by said spring to seat the valve, and a casing supporting said valve on said engine and removable axially therefrom, said first lever having a clearance with respect to the axial projection of said casing, said 70 second lever being pivoted on said casing and removed with said casing independently of said first lever.

9. A fuel injection apparatus for engines of the fuel injection type including, a fuel injection 75

valve unseated by fuel pressure, a valve controlling device, a spring, a lever mechanism cooperating therewith and consisting of first and second pivoted levers, said first lever engaging the spring and directly actuated by said device independently of said second lever to compress the spring, said second lever engaging said injection valve and actuated by said spring to seat the valve,

and a casing removably supporting said valve on said engine, said second lever having one arm overlying an arm of said first lever and being pivoted on said casing, said second lever being removable with said casing independently of said first lever.

EDWARD T. VINCENT.
